[57] **CLAIM**

The ornamental design for a folded frame for an electric solenoid, as shown.

DESCRIPTION

FIG. 1 is a reduced perspective view of a folded frame for an electric solenoid showing my new design; FIG. 2 is a side elevational view thereof, the opposite side being a mirror image;

FIG. 3 is an end elevational view taken from the right of FIG. 2;

FIG. 4 is an end elevational view taken from the left of FIG. 1;

FIG. 5 is a bottom plan view thereof;

FIG. 6 is a top plan view thereof.

FIG. 1

FIG. 2

FIG. 3

FIG. 4

FIG. 5

FIG. 6
